UNITED STATES PATENT OFFICE.

MAX SCHEY, OF BROOKLYN, NEW YORK.

SPIT SUPPORT FOR ROTISSERIES.

Application filed October 28, 1920. Serial No. 420,189.

To all whom it may concern:

Be it known that I, MAX SCHEY, a citizen of the United States, residing at New York city, borough of Brooklyn, in the county of 5 Kings and State of New York, have invented a certain new and useful Spit Support for Rotisseries, of which the following is a specification.

This invention relates to machines or apparatus for broiling meats or poultry which machines are generally known to the trade as rotisseries. In such machines as heretofore made, the spits are usually supported one above the other before the fire which 10 may be a gas burner or a bed of hot coals, and are adapted to be rotated so as to present all portions of the roasts to the heat. Such spits are usually journaled for rotation in angle brackets rigidly secured to the frame 15 or in holes or slots formed in one of the uprights of the frame. In any event, the mounting of the spits is such that while they may be freely rotated, or removed from or replaced in the frame of the machine, their 20 roasting position with reference to the fire is fixed and predetermined.

When large roasts are positioned on the spits of this character, they extend much closer to the fire than relatively smaller 25 roasts and are much more apt to burn than such smaller roasts which are positioned much further away from the source of heat. Moreover, some meats require for proper roasting a relatively slow cooking, such as as 30 would be obtained if the roasts were further away from the fire, while other roasts require more rapid cooking, such as could be accomplished by positioning them closer to the source of heat. This regulation of the heat 35 in prior rotisseries has usually been accomplished by regulating the intensity of the fire by supplying more gas in a gas rotisserie or by running a hotter fire in a coal rotisserie.

With these considerations in mind, the object of the present invention is to provide a mounting for spits whereby they may be bodily shifted together with their rotating means in a position toward and away from 40 the fire, so that the heat to which the roasts of the respective spits are subjected may be regulated with more nicety.

A further object of the invention is to so mount the spits that all of them may be 45 moved in unison and from a convenient point so far from the fire that the prime mover of

the operating means will not become hot and render its handling liable to burning the hands of the chef.

Features of the invention, other than those 60 adverted to, will be apparent from the hereinafter detailed description and claims, when read in conjunction with the accompanying drawings.

The accompanying drawings illustrate one 65 practical embodiment of the present invention, but the construction therein shown is to be understood as illustrative, only, and not as defining the limits of the invention.

Figure 1 of the drawing illustrates in perspective the present invention associated with a rotisserie which, in the interest of clearness, is shown in phantom, and

Figure 2 is a like view illustrating a modified form of spit driving means.

In the accompanying drawings, A designates a rotisserie, the outlines of which are shown in phantom and B designates one of a plurality of spits to be used in conjunction with the rotisserie. Any number of spits 80 may be employed depending upon the capacity of the rotisseries, which, in practice, are made of different numbers of spits and of different sizes.

In the carrying out of the present invention, instead of mounting the spits rigidly on the frame of the machine or on rigid brackets attached thereto, the spits are carried on and supported by the swinging brackets C and C', one of which is pivoted at 90 each side of the machine. Each of the brackets C and C' is provided with slots or bayonet shaped joints c adapted to receive the spits so that when the spits are brought into engagement with the slots c, they will be supported after the manner shown in the drawing in a horizontal position before the fire and in such manner that they may be freely rotated.

The upper end of the bracket C' is pivoted 100 at d' and the upper end of the bracket C is pivoted on a spindle d which also carries a gear D and a sprocket E. The gear D and sprocket E are secured together for simultaneous rotation and when the former is 105 driven by suitable mechanism, the latter is operated therewith to drive the sprocket chain e, which is looped about a second sprocket F carried by a yoke f which is firmly supported on and carried by the lower 110 end of the bracket C. Each of the spits has affixed to one end thereof a sprocket B' and

the sprocket wheels E and F are so positioned that when the spit is brought into engagement with the slots of the brackets, the sprocket on each spit will automatically mesh 5 with one reach of the sprocket chain e as shown. In order to assure proper driving relation, the driving reach of the sprocket chain e is preferably backed up by a channel member G supported from the bracket C by 10 means of angle pieces g and this channel member precludes the sprocket chain from backing off the sprockets of the respective spits.

This arrangement of chain and sprocket 15 drive mechanism operates with great efficiency in practice and proper cooperation between the driving chain and the spit sprocket is assured during all adjustments of the brackets to bring the spits closer or 20 further away from the fire. It should be understood, however, that the chain and sprocket drive is illustrative only of any equivalent drive which may be used for this purpose, such, for example, as a worm and 25 worm gear drive shown in Figure 2 of the drawings. The essential feature is that when the spits are dropped into the slots, they will automatically engage with the driving means.

30 Extending transversely through the machine in the forward portion thereof is a rock shaft H, journaled for rotation in the frame and having fixed at its opposite ends a pair of curved arms h and h', which are 35 slotted at I, and I'. The slot I is adapted to embrace a pin i on the bracket C, while the slot I' similarly cooperates with a pin i' on the bracket C', so that when the rock shaft is oscillated, the pin and slot connections described will simultaneously effect a pivotal 40 movement of both brackets in a direction toward or away from the fire depending upon the direction of the oscillation of the rock shaft. This movement of the rock shaft may 45 be readily provided for by extending the arm h in a forward direction as at h² and providing the same with a handle J by means of which pivotal movement may be imparted to the rock shaft for the purposes 50 stated. By grasping the handle J and raising or lowering the same, both brackets may be moved toward the fire or away from the same as desired to bring the spits into a greater or lesser proximity to the fire. In 55 this manner, roasts on the spit may be brought into proper roasting relation to the source of heat and the chef is at all times able to properly control the cooking of the same.

60 The brackets may be locked in any desired position by suitable means such as a latch K pivoted at k and having its lower edge serrated as shown, so that it will engage with an extension of the pin i to hold the 65 bracket C in any one of its several positions.

In the construction shown the lifting of the latch and the holding of the same in raised position will allow all of the spits to swing into close proximity to the source of heat. When the brackets are swung downwardly 70 by manipulation of the handle J, the latch, being gravity operated, will automatically lock the parts in the positions which they occupy when the chef discontinues the operations of the handle. 75

In Figure 1 of the drawings, the spits are driven, as described, by means of the sprocket chain with which all of the sprockets of the spits are adapted to engage. In Figure 2, a modified form of construction is 80 illustrated. In this view a structure is shown wherein the sprocket B' is replaced by a worm gear B², so that each spit carries a worm gear instead of a sprocket gear. Each worm gear B² is adapted to mesh, 85 when the spit is in the machine, with a worm P, and all of these worms are fixed to a common shaft. The upper end of the shaft is rotatably supported in a cylindrical hole in the bottom of a bearing block O and 90 is free to rotate therein, while the lower end of this shaft is journaled for rotation in a bracket f', corresponding to the bracket f and carried by the part C.

The bearing block O is rotatably supported on a spindle d², corresponding to the spindle d, on which the bracket C is adapted to swing, so that by this construction, the worm gears B² of all the spits will be in mesh with the corresponding worms of the 100 shaft N irrespective of the movement of the brackets C and C' to bring the spits closer to or further away from the fire. 95

The shaft N is driven from the prime mover D through bevel gears L and M, which are respectively fixed to the prime mover and to the shaft N, so that swinging movement of the brackets will in nowise interfere with the drive of the spits. In 105 order to maintain the gear B² of each spit in proper driving relation with its corresponding worm P, each spit is preferably provided with a pair of collars b, which preclude longitudinal movement of the spit. 110

The spit supporting means of the present 115 invention is extremely simple in construction, may be readily associated with almost any type of rotisserie and is thoroughly efficient in the carrying out of its intended purposes. The structure shown in the drawings 120 is that which is preferably employed and it is to be understood that the invention is susceptible to modifications in details of construction which would naturally follow in the adaptation of the invention to different 125 forms of rotisserie. Moreover, mechanical equivalents may be substituted without departing from the spirit of the invention which is to be understood as broadly novel as 130 is commensurate with the appended claims.

Having thus fully described the invention, what I claim as new and desire to secure by Letters Patent is:

1. A rotisserie embodying a spit, a pair of pivoted brackets adapted to collectively support the spit for adjustment toward and away from the fire, means for simultaneously pivotally moving both brackets to vary the distance between the spit and the fire, and means for driving the spit irrespective of its position with reference to the fire.
2. A rotisserie embodying a pair of pivoted brackets, a spit rotatively supported by said brackets, means for pivotally moving both brackets simultaneously to vary the distance between the spit and the fire, a gear on the spit and a drive chain bodily movable with the brackets and adapted to mesh with the gear on the spit irrespective of the position of the brackets with relation to the fire.
3. A rotisserie embodying a plurality of spits, a pair of pivoted brackets adapted to demountably support said spits in a position forwardly of the fire, means for pivotally moving the brackets to vary the distance between the spits and the fire and driving connections common to all the spits and adapted to rotate the same irrespective of the position of the brackets with relation to the fire.
4. A rotisserie embodying a plurality of spits, a pair of pivoted brackets adapted to demountably support said spits in a position forwardly of the fire, means for pivotally moving the brackets to vary the distance between the spits and fire, a sprocket on each spit and a drive chain mounted for bodily movement with the brackets and adapted to mesh with all of the spits irrespective of the position of the brackets with relation to the fire.
5. A rotisserie embodying a plurality of spits mounted for simultaneous adjustment in a direction toward and away from the fire, a drive member on each spit, and common driving means cooperating with the drive members of all the spits for effecting rotation of the spits irrespective of their positions relative to the fire.
6. In a rotisserie, a plurality of spits, unitary means for supporting all of the spits, said means being pivotal, whereby it may be pivotally moved to simultaneously bring all the spits closer to the fire or further away from the same.
7. A rotisserie embodying a pair of brackets, each of which is pivotally supported at its upper end and each of which embodies means for supporting one end of a plurality of spits, a plurality of spits each of which is provided on one end with a permanently fixed sprocket, a rock shaft mounted for oscillation, a pair of curved slotted arms fixed on the rock shaft, pins on the brackets extending through the slots of the curved arms and means for oscillating the rock shaft to operate the curved arms for the purpose of pivotally moving the brackets to vary the distance between the spits and the fire, in combination with an endless drive chain, a pair of sprockets about which said chain passes, one of said sprockets being supported by one of the brackets in a position to maintain the chain in engagement with the sprockets of all of the spits, irrespective of the position of the brackets with reference to the fire.
8. A rotisserie embodying a pair of brackets, each of which is pivotally supported at its upper end and each of which embodies means for supporting one end of a plurality of spits, a plurality of spits each of which is provided on one end with a permanently fixed sprocket, a rock shaft mounted for oscillation, a pair of curved slotted arms fixed on the rock shaft; pins on the brackets extending through the slots of the curved arms and means for oscillating the rock shaft to operate the curved arms for the purpose of pivotally moving the brackets to vary the distance between the spits and the fire, in combination with an endless drive chain, a pair of sprockets about which said chain passes, one of said sprockets being supported by one of the brackets in a position to maintain the chain in engagement with the sprockets of all of the spits, irrespective of the position of the brackets with reference to the fire.
9. In a rotisserie, a plurality of spits, a spit supporting frame on which all of the spits are mounted, said frame being in turn mounted for movement toward and away from the fire, whereby it may be moved to simultaneously bring all of the spits closer to the fire or further away from the same, a prime mover, and operative connections between the prime mover and the several spits, irrespective of the position of the spits, so that the spits can be constantly driven, while in any fixed position, as well as during movement from one position to another.
10. In a rotisserie, a spit support mounted for movement toward and away from the fire and adapted to support a spit from both ends thereof with the spit in a substantially horizontal position, at least one spit mounted for horizontal axial rotation on said support, whereby the support may be moved to bring the spit closer to the fire or further away from the same, a prime mover, and operative connections between the prime mover and the spit, irrespective of the position of the support, so that the spit can be

constantly driven while in fixed position as well as during movement from one position to another.

11. In a rotisserie, a spit support mounted for pivotal movement on a horizontal axis toward and away from the fire and adapted to support a spit from both ends thereof with the spit in a substantially horizontal position, at least one spit mounted for rotation on said support, whereby the support may be pivotally moved to bring the spit closer to the fire or further away from the same, a prime mover, and operative connections between the prime mover and the spit, irrespective of the position of the support, so that the spit can be constantly driven while in fixed position as well as

during movement from one position to another.

12. In a roasting machine of the character described, a pair of frames arranged adjacent a heating element, a plurality of spits carried by each of said frames, a power shaft pivotally supporting one side of said frame, a plurality of secondary shafts mounted on said frames, a power unit connected to said power shaft, means transmitting the rotation of said power shaft to said secondary shafts, and means connected to the lower end of each frame for swinging the same to and from said heating element.

In testimony whereof, I have signed my name to this specification.

MAX SCHEY.
